UNITED STATES PATENT OFFICE.

VEEZEE E. BOWMAN, OF MCKEES ROCKS, PENNSYLVANIA.

NIPPERS.

1,317,424.

Specification of Letters Patent. Patented Sept. 30, 1919.

Application filed January 15, 1919. Serial No. 271,226.

To all whom it may concern:

Be it known that I, VEEZEY E. BOWMAN, a citizen of the United States, residing at McKees Rocks, in the county of Allegheny and State of Pennsylvania, have invented 5 certain new and useful Improvements in Nippers, of which the following is a specification.

This invention relates to new and useful 10 improvements in a device known in police parlance as nippers, and the primary object thereof is to provide a device of the character described to facilitate the subjection and control of an unruly captive or 15 prisoner by the officer of the law.

Other objects of this invention are to provide a device of the type set forth which is spring operated to lock upon the wrist of a prisoner, which is simple in its construction 20 and arrangement, strong, durable and efficient in its use and inexpensive to manufacture.

To the accomplishment of these and such other objects as may hereinafter appear the 25 invention consists of the novel construction, combination and arrangement of parts herein specifically described and illustrated in the accompanying drawings wherein is shown an embodiment of the invention.

30 In the drawings forming a portion of this specification and wherein like numerals of reference designate corresponding parts throughout the several views:

Figure 1 is a plan view of the nippers 35 embodying the invention with the casing and the locking chamber shown in cross section.

Fig. 2 is a vertical side view of the nippers.

40 Fig. 3 is a vertical side view with a portion of the casing in cross section.

Fig. 4 is a vertical side view of the grip handle and associated parts.

Fig. 5 is a view on line α — α , Fig. 1.

45 Fig. 6 is a modification of the nippers with the casing in cross section.

Fig. 7 is a side elevation thereof.

Fig. 8 is a fragmentary side view of the casing with the operating ring and the 50 spring lock mounted thereon.

Fig. 9 is a sectional view of the casing

neck with the stem mounted therein, and illustrating manner of mounting the spring lock.

Referring more in detail to the drawings 55 there is shown in Fig. 1 the nippers embodying the invention and comprising the casing 1 having the neck 2 formed integrally therewith. The arm 3 is securely fixed in the casing 1 by means of the rivets 4 and 60 carries the locking chamber 5.

The gripping handle 6 is formed integrally with the stem 7 which is provided with the thread 8 adapted to engage in the threaded aperture 9 in the neck 2. A collar 65 10 is fixed on the stem 7 in the casing 1 to limit the upward movement of the stem 7 in the threaded aperture 9.

The jaw 11 is pivotally mounted at 12 in the casing 1 and is provided with the serrated end 13 which is adapted to be engaged by the lock spring 14 in the locking chamber 5.

The curvature of the lower portion 15 of the casing 1 combined with the curvatures 75 of the arm 2 and the jaw 11, are such that the combination conforms as nearly as possible to the contour of the average wrist.

The operating rod 16, pivotally connected at 17 to the jaw 11, extends vertically 80 through the aperture 18 in the top of the casing 1 and is formed with the ring 19^a for the insertion of the finger when operating the device. The spiral spring 19, mounted on the operating rod 16, is normally in the 85 expanded position and tends to force the jaw 11 to the locked position in the locking chamber 5.

The lock spring 14 is riveted at 20 to the locking chamber wall 21 and engages the 90 serrated end 13 of the jaw 11 when the latter is forced into the locking chamber 5 by the action of the spring 19 or by the manipulation of the gripping handle 6. The spring 14 is disengaged from the serrated 95 end 13 of the jaw 11 by the use of a key (not shown) which is adapted to operate through the key-hole 22.

For the purpose of holding the spring 14 disengaged from the serrated end 13 of 100 the jaw 11, when the nippers are not in use, there is provided a pin 23 fixedly riveted

to the spring 14 which carries the rectangular catch 24 having a swivel connection therewith. A rectangular slot 25 is formed in the locking chamber 5 opening outwardly 5 through the chamber wall 21. When the locking spring 14 is in the operative position the catch 24 will be extending parallel with the slot 25 and move freely therein, but when it is desired to bring the spring 14 10 to the inoperative position the spring 14 is disengaged by means of the key which forces the catch 24 out through the chamber wall 21. The catch 24 being swiveled to the pin 23 is given a turn to extend at right-angle 15 with respect to the slot 25 and will hold the spring 14 in the inoperative position until the catch 24 is again turned to extend parallel to the slot 25.

The stem 7 has a swivel connection with 20 the tightening cam 26 in the casing 1. The tightening cam 26 is mounted for vertical movement in the casing 1 by the rotation of the stem 7 in the threaded aperture 9 in the neck 2. The tightening cam 26 is provided with the beveled end 27 which is adapted to engage the vertically extending beveled end 28 of the jaw 11 and force the jaw 11 tightly around the wrist of the prisoner. The end 29 of the tightening cam 26 25 acts against the arm 3 which serves as a guide therefor.

In practice the operation of the device is as follows: The officer of the law first 30 throws the catch 24 to bring the spring 14 to the operative position. He then grasps the gripping handle 6 with one finger in the ring 19^a and pulls the operating rod 16 upwardly toward the handle 6 which opens the jaw 11. The jaw 11 is thrown or placed 35 upon the wrist of the prisoner and the ring 19^a released which will cause the spring 19 to force the jaw 11 to the closed or locked 40 position in the locking chamber 5.

If the prisoner proves unruly after the 45 device is placed on his wrist as herein above described, the officer gives the gripping handle 6 a turn which forces the cam 26 downwardly to act against the beveled end 28 of the jaw 11 and forces the jaw still 50 more tightly around the wrist of the prisoner.

In the modification shown in Fig. 6 of the drawings, two jaws 30 and 31, pivotally mounted in the casing 32 at 33 and 34, respectively, are provided which are simultaneously operated by the operating member 35, which comprises the rods 36 and 37 pivotally connected at 38 and 39 to the jaws 30 and 31. The rods 36 and 37 are securely 55 fixed to the cross-bar 40 which is provided with the centrally located opening 41 which encircles the neck 42 of the casing 32. A ring 43 is mounted on one side of the cross-bar 40 for manipulating the operating mem-

ber 35. Spiral springs 44 and 45 are respectively mounted on the rods 36 and 37 for the purpose and forcing the jaws 30 and 31 to the closed position. A groove 46 is formed in the neck 42 in which is mounted a notched spring 47 by the rivet 48. The 60 spring 47 normally stands outward from the groove 46 as shown in Fig. 9 and is adapted to engage the upper face of the cross-bar 40 and prevent the upward movement of the operating member 35 and lock 75 the jaws 30 and 31 upon the wrist of the prisoner. For opening the jaws 30 and 31 the spring 47 is forced into the groove 46 by pressure upon the button 49 while drawing the operating member 35 upwardly. 80

The cam 50, having a swivel connection with the stem 51, is provided with the beveled ends 52 and 53 which engage the respective jaw ends 54 and 55, and when moved downwardly by the rotation of the stem 51 causes the jaws 30 and 31 to close tightly upon the wrist. The jaw ends 56 and 57 instead of abutting as shown in Fig. 6, may be made with respective interfitting male and female ends. 90

Suitable cover plates are provided for the casings in the preferred and modified forms of the device and may be either riveted or fastened with screws as desired.

It will be noted that the respective casings 95 are provided with slots to permit the ample movement of the jaws therein.

From the foregoing description taken in connection with the accompanying drawings, the advantages of the construction and the 100 method of operation will be readily apparent to those skilled in the art to which the invention appertains, and while describing the principle of operation of the invention together with the device which is now considered to be the best embodiment thereof, it is to be understood that the device shown is merely illustrative and that various 105 changes in the form, proportion and the minor details of construction may be resorted to without departing from the principle or sacrificing any of the advantages of the invention as defined in the appended claims.

What I claim as new and desire to secure 115 by Letters Patent is:

1. A manacle comprising a casing having a neck provided with a threaded aperture, a stem having a screw connection in the said threaded aperture, a gripping handle formed 120 integrally with the said stem, an arm carrying a locking chamber fixedly mounted in the said casing, a jaw pivotally mounted in the said casing, an operating rod, a spring for automatically locking the said jaw in 125 the said locking chamber mounted on the said operating rod, and a cam carried by the said stem adapted for forcing the said jaw

into the said locking chamber by rotating the said gripping handle.

2. A manacle comprising a casing, a gripping handle having a stem formed integrally therewith, said stem having a screw connection in the said casing, a pair of jaws hingedly connected in the said casing, an op-
- erating member for forcing the said jaws to the closed position, means for locking the said jaws in the closed position, and a cam 10 carried by the said stem for still further closing the said jaws.

In testimony whereof I affix my signature.

VEEZEY E. BOWMAN.
